ADJUSTABLE BAR FOR BLOCKING SLIDING DOORS AND WINDOWS

Clarence D. Williams, Los Angeles, Calif. (20227 Itasca
St., Chatsworth, Calif. 91311), and Francis M. Arch-
dekin, 2721 W. Verdugo, Burbank, Calif. 91505

Filed Dec. 10, 1973, Ser. No. 423,421

Term of patent 14 years

Int. Cl. D8—07

U.S. Cl. D8—203

FIG. 1 is an isometric view of an adjustable bar for blocking sliding doors and windows, showing our new design;

FIG. 2 is an end view thereof;

FIG. 3 is a view of the opposite end thereof;

FIG. 4 is a top view thereof; and

FIG. 5 is a side view thereof.

We claim:

The ornamental design for an adjustable bar for blocking sliding doors and windows, substantially as shown.
